BRASSIÈRE AND SIMILAR GARMENT

Edwin W. Gluckin, Brooklyn, N. Y.

Application February 22, 1945, Serial No. 579,188

2 Claims. (Cl. 2—42)

1

This invention relates to garments employing pockets with means for supporting the pockets upon the body of the wearer. More particularly, the invention deals with garments of this class employing supplemental breast supporting members as part of the pocket structure, and preferably arranged within the pockets, the supporting members being what might be termed hammocks, by reason of the relatively free hanging and support thereof within the pockets. Still more particularly, the invention deals with garments of the kind wherein the hammocks or supports have means adjustable coupling parts thereof in the pockets in controlling the positioning of the hammocks with respect to the pocket structures of the garments. The novel features of the invention will be best understood from the following description when taken together with the accompanying drawing, in which certain embodiments of the invention are disclosed, and in which the separate parts are designated by suitable reference characters in each of the views, and in which:

Fig. 1 is a front perspective view of a brassière made according to my invention.

Fig. 2 is an inside view of the front portion only of the brassière shown in Fig. 1.

Fig. 3 is a diagrammatic view illustrating parts of the brassière in separated or expanded position to illustrate the adjustable coupling of the hammock structure in the brassière structure; and

Fig. 4 is a perspective view of the upper portion of one of the pockets illustrating the manner of coupling the shoulder strap with the brassière pocket and hammock.

In Figs. 1 and 2 of the drawing is shown front and rear views of at least the front portion of the garment or brassière. In these figures, 10 and 10a represent two substantially similar pockets joined centrally of the garment, as indicated at 11. Attached to outer side portions of the pockets are side and back bands 12 and 13 detachably coupled, as seen at 14 in any desired manner, as is customary in garments of this type and kind. One of the bands, for example, the band 13 may include an elastic insert 15 to provide yieldable mounting of the garment upon the body of the wearer. At the upper central portion of each pocket is secured a strap or loop 16 and 17 with which is adjustably coupled shoulder straps 18 and 19 through the medium of buckles 20 and 21, the straps 18 and 19 being attached to the bands 12 and 13 at the rear portions thereof, as indicated at 22 and 23.

In the brassière as illustrated in the accom-

panying drawing, the pockets 10 and 10a are shown of a simple form, that is to say, composed of a single sheet of material in which is formed darts 24 and 25 to give breast-conforming contour to the pockets. It is here to be noted, however, that my invention is not particularly concerned with just how the pockets or cups of the garment are constructed.

In the present construction, the brassière also includes a body band 26 attached to the lower portions of the pockets and to the side bands 12 and 13, the latter being made sufficiently wide to accommodate outer sides of the pockets as well as the ends of the bands 26. Here again it will be apparent that my invention is not limited to use in connection with brassières or other garments which include band portions or any other garment parts, as the invention is concerned primarily with the breast supporting pocket or cup area of the garment.

Arranged within the pockets or cups 10 and 10a are supplemental supporting members 27 and 28, which members may be termed, for sake of description, hammocks, in that they provide independent hanging type of supports disposed on each pocket or cup, and arranged to extend over the lower central and inner and outer side portions of the breasts when arranged therein.

The members 27 and 28 may be composed of any desired material, but are preferably composed of a pad like structure considerably heavier than the fabric of the pockets 10 and 10a, and may have elastic properties or comprise a body of lastex. Upper edges 29 and 30 of the members 27 and 28 are preferably rounded to fit around the breasts at a point adjacent but beneath the nipples. Outer ends of the members have upwardly directed extensions 31 and 32 with which are connected supporting straps 33 and 34. Inner ends 40 of said members have extensions 35 and 36 with which other strap members 37 and 38 are connected. Upper ends of the strap members 33—38 and 34—37 are joined, as seen at 39 and 40, and to these joined ends are connected one end of the supporting straps or loops 16 and 17, the other ends of the straps or loops being joined to the upper ends of the pockets 10 and 10a. It will also appear that the straps 16 and 17 pass freely through the buckles 20 and 21 in providing relative movement of the strap ends in independent support of the members 27 and 28 and the pockets 10 and 10a.

The structure of the members 27 and 28 and their supporting straps is shown most clearly in Fig. 2 of the drawing. The members 27 and 28

terminate short of the central coupling 11 of adjacent pockets and these ends are joined by an elastic strap 41, the other ends of the members 27 and 28 are joined to the outer edges of the pockets or to the bands 12 and 13, as seen at 42 and 43.

Aside from attachment of the members 27 and 28, as at 42 and 43, these members are hung freely within the pockets of the garment. However, in some uses of the garment, it will be desirable to maintain the adjacent-coupled end of the members or the strap 41 thereof in predetermined position on the garment. To this end the inner surface of the coupling, as at 11, which may be in the form of a finishing tape, will include a plurality of vertically spaced buttonholes or coupling bars 44 with which a hook 45 supported centrally of the lower edge portion of the member 41 is adjustably coupled. In this way, the height of the hammock units at the central front portion of the garment may be adjustably regulated. This latter construction is shown in the diagrammatic illustration in Fig. 3 of the drawing where the central portion of the hammock is shown turned back in order to illustrate the openings or coupling bars 44 and to clearly show the supporting hook.

When the members 27 and 28 are composed of elastic material, the supporting straps 33-34 and 37-38 need not be of elastic material nor have elastic inserts therein. However, they may be so made, if the members 27 and 28 are of non-extensible material, particularly when it would be desirable to provide resiliency of the mounting in the hammocks in the garment.

The hammocks may be said to take the primary load of the breasts in supporting the same in raised youthful position, and the remainder of the garment shaped to fit snugly upon the supported breasts, it being understood that the size of the pockets of cups as well as the members 27 and 28 will be made to suit the various cup sizes in different sized garments of the class under consideration.

It will also be apparent that the attachments of the hammocks with the central lower portion of the garment will also aid in maintaining the hammocks or the adjacent end portions thereof snugly around the breasts and closely adjacent the body of the wearer intermediate the breasts. In some types of garments where sizes can be more definitely and positively controlled, and particularly in tailored garments, the attachment between the strap 41 and the central portion of the brassière may be made permanent by stitching or otherwise. On the other hand by the standpoint of adjustment, any type and kind of couplings or fastenings can be employed.

In supporting members or hammocks 27 and 28 together with the straps 33-38, 34-37, the strap 41 may be said to constitute a breast supporting unit adapted to be built into any type or kind of garment. This unit may be built into the garment by the manufacturer, and from this standpoint sold as a unit article of manufacture to different

garment manufacturers. On the other hand, this unit may be sold directly to the consumer for installation in garments of various kinds and classes.

Having fully described my invention what I claim as new and desire to secure by Letters Patent is:

1. A garment of the class described comprising breast supporting pockets, means for supporting

10 the pockets upon the body of a wearer, a hammock-type support arranged at the lower portion of each pocket, means at the outer end portion only of each support maintaining predetermined fixed position of the support on the pocket, the

15 remainder of each support being free, a curved strap structure at the upper portion of each pocket, said strap structure being coupled with the outer end portion of one support and the inner end portion of an opposed support and freely

20 movable in the pockets, a member coupling adjacent inner end portions of said supports, and short strap loops coupling upper portions of said strap structures and pockets for hanging the supports in connection with the pockets.

25 2. A garment of the class described comprising breast supporting pockets, means for supporting

the pockets upon the body of a wearer, a hammock-type support arranged at the lower portion of each pocket, means at the outer end portion

30 only of each support maintaining predetermined fixed position of the support on the pocket, the remainder of each support being free, a curved strap structure at the upper portion of each pocket, said strap structure being coupled with

35 the outer end portion of one support and the inner end portion of an opposed support and freely movable in the pockets, a member coupling adjacent inner end portions of said supports, short strap loops coupling upper portions of said strap structures and pockets for hanging the supports in connection with the pockets, and means adjustably coupling the member joining adjacent inner ends of the supports with the garment intermediate said pockets.

EDWIN W. GLUCKIN.
